UNITED STATES PATENT OFFICE

99,740

DESIGN FOR A TAILLESS MONOPLANE WITH LONGITUDINAL SIDE WINGS

Edward F. Wagner, Philadelphia, Pa.

Application February 6, 1936, Serial No. 60,994

Term of patent 3½ years

To all whom it may concern:

Be it known that I, Edward F. Wagner, a citizen of the United States, residing at Philadelphia, in the county of Philadelphia and State of Pennsylvania, have invented a new, original, and ornamental Design for a Tailless Monoplane with Longitudinal Side Wings, of which the following is a specification, reference being had to the accompanying drawings, forming a part thereof.

Fig. 1 is a side elevation of the monoplane showing my new design.

Fig. 2 is a top plan view thereof.

Fig. 3 is a similar view with the wings folded.

Fig. 4 is a front elevation of the monoplane.

I claim:

The ornamental design for a tailless monoplane with longitudinal side wings, as shown.

EDWARD F. WAGNER.
